(57) **CLAIM**

The ornamental design for a data receiver and transmitter, as shown and described.

DESCRIPTION

FIG. 1 is a back side view of a data receiver and transmitter of the present invention.

FIG. 2 is a front side view of the data receiver and transmitter of FIG. 1.

FIG. 3 is a left side view of the data receiver and transmitter of FIG. 1.

FIG. 4 is a right side view of the data receiver and transmitter of FIG. 1.

FIG. 5 is a top side view of the data receiver and transmitter of FIG. 1.

FIG. 6 is a bottom side view of the data receiver and transmitter of FIG. 1.

FIG. 7 is a rear, left-side perspective view of the data receiver and transmitter of FIG. 1; and,

FIG. 8 is a front, right-side perspective view of the data receiver and transmitter of FIG. 1.

The broken lines in the drawings are used to show portions of the data receiver and transmitter that do not form part of the claimed design.
